IMPREGNATION OF ELECTRIC CABLES

Thomas Robertson Scott and John Krauss Webb,
Aldwych, London, England, assignors to International Standard Electric Corporation, New York, N. Y., a corporation of Delaware

Application July 19, 1932, Serial No. 623,310
In Great Britain October 12, 1931

14 Claims. (CL 173—264)

This invention relates to a system and method for feeding degasified oil or the like into an electric cable and is particularly suitable for use in the impregnation of paper insulated power cable. An object of the invention is to reduce to a minimum the risk of feeding contaminated oil to the cable and another object is to provide a ready and practical method and system for effecting said impregnation.

10 According to one feature of the invention a system or method of feeding under pressure degasified oil or the like into a cable is arranged so that the rate of degasification of the oil is determined automatically or continuously by 15 the cable consumption.

Another feature is maintaining substantially uniform the pressure in the oil as it is fed to the cable irrespective of the rate of oil consumption by the cable.

20 According to another feature of the invention the system or method comprises a pump operating to discharge a supply of degasified oil from a source to a cable or to intermediate apparatus before reaching a cable, said pump also being 25 adapted to discharge a supply of oil to said source for degasification.

Another feature of the invention is a particular form of the degasifier unit as will be hereinafter explained.

30 These and other features of the invention will be more readily understood from a perusal of the following description having reference to the accompanying drawings in which Figure 1 schematically illustrates a system according to 35 the invention. Figure 2 illustrates schematically a form of the degasifier unit which may be employed in the system of Figure 1 and Figure 3 illustrates a system which is a modified form of that shown in Figure 1.

40 In Figure 1 a piston 1 is adapted to operate in the cylinder 2. This cylinder has an inlet valve 3 over which the cylinder communicates with an inlet pipe 4 connected to some suitable oil supply 5. The source 5 is shown schematically 45 and may comprise any known arrangement for maintaining a head of oil to the inlet pipe 4. An outlet valve 6 communicating with the pipe 1, affords access of oil from the chamber 2 to a reservoir 8 connected to a degasifier 9 from 50 which oil is fed to a reservoir 10. A pipe 11 connects the outlet of the reservoir 10 to the inlet valve 12 of the chamber 2. A pipe 13 maintains continuous connection between the chamber 2 and a pressure compensating chamber 14. This 55 chamber has a piston 15 whose level depends

upon the pressure in the chamber 2 below the piston 1. The chamber 14 has an outlet valve 16 leading to a cock which may be used to couple the cable to this outlet of the chamber 14. Another outlet valve 17 leads to pipes 18 and 19 which communicate with the reservoir 20, degasifier 21 and the reservoir 22, the latter being connected over a pipe 23 and inlet valve 24 to the chamber 14. An auxiliary pipe 25 containing a hand operated regulating valve 25' also connects the chamber 14 with the pipe 18, and forms a regulating by-pass around the chamber 14, pipe 18 and the oil sealing system 31. The piston 1 carries weights 26 and is connected by means of a rope 27 to a capstan 28 which may be operated over a magnetic clutch 29 by a motor 30.

The various cocks in the system are preferably oil sealed and a continuous supply of oil to this seal system is effected over the pipe 18 the rectangle 31 representing schematically the entire oil seal system.

The operation of the arrangement is as follows:—

The incoming oil is fed from the source 5 and is preferably under a gravity head and at some degree of reduced gas content (say 50%), designated herein as "stage '0'". The downward stroke of the piston 1 sucks the oil into chamber 2 through the non-return valve 3. The displacement capacity of this chamber is designed to give the desired volume 'v' which it is proposed to circulate through the system by each stroke of the piston 1. The upward stroke of the said piston causes oil to pass through the non-return valve 6 to the reservoir 8 which preferably has a capacity in excess of 'V' the exact value being calculated in terms of the rate of flow in the degasifier 9 and the maximum number of strokes per unit of time which said piston may be required to make. The oil from the degasifier 9 collects in the reservoir 10 which is preferably of about the same capacity as the reservoir 8. On the upward stroke of the piston 1 oil (hereinafter termed "stage 1 oil") is sucked from the reservoir 10 into the chamber 2 through the pipe 11 and non-return valve 12. The suction is caused by the upward motion of the piston 1 and is limited to the second half of the upward stroke by a sleeve 32 which is attached to the piston.

The maximum capacity of chamber 2 below the piston is $2V$ and the remaining volume V required is obtained by drawing back, during the first half of the stroke, a volume v equal to 55

the displacement volume of chamber 14 below the piston in the raised position. The upward stroke of the piston is made by automatically switching-in an electric motor and winding gear 5 when the piston 1 reaches the bottom of its stroke. The switching-in may be carried out by starting up a motor which is coupled to the winding gear, or by actuating a magnetic clutch between the winding gear and a motor which is 10 running continuously. The winding gear is switched out at the top of the piston's stroke, and the downward stroke is controlled by the weight system (regulating the pressure) and the demand of the cable, or the impregnating system for oil. The downward stroke sucks stage 0 oil into chamber 2 as described above, and also forces stage 1 oil from chamber 2 to chamber 14. The piston 15 is thus caused to move upwards. The piston 15 reaches the top of its stroke during the first half of the downward stroke of the piston 1. At this point the sleeve attached to piston 15 exposes an outlet in chamber 14, and during the second half of the downward stroke of piston 1, a volume V of stage 1 oil is passed 25 from chamber 2 via chamber 14 to reservoir 20. In passing from chamber 14 to reservoir 20 the oil traverses a non-return valve and the oil seal system 31. 20 is the reservoir for the stage 2 degasifier and is a replica of reservoir 8. The 30 oil passes through the degasifier as described above to reservoir 22 and is drawn thence to chamber 14 through a non-return valve. The suction in this case is caused by the downward stroke (under gravity) of piston 15 during the 35 first half stroke upwards of piston 1. From chamber 14 the oil is forced under pressure through a non-return valve and a hand operated "shut-off" valve to the cable or to the impregnating system. The pressure is supplied 40 through piston 15 during the downward stroke of piston 1. The maximum volume of chamber 14 (below its piston) is V so that as the cable takes this volume the stage 2 degasifier is replenished by the completion of the stroke 45 of piston 1, and, as described above, a fresh supply of oil (volume V) is taken into the system and passed through the stage 1 degasifier.

In place of the sleeve valves shown attached to pistons A and B, it may be convenient to utilize 50 outside valves controlled by the action of the piston rod of piston 1. These valves would be operated to open during the second half of the upward and downward strokes respectively of piston 1, say by a sleeve action on the valve rod 55 such that relative motion between the valve rod and the piston 1 rod was permitted during the first half of the upward stroke.

The degasifier is illustrated in more detail in Figure 2. It is built up of a plurality of fluted 60 cylinders 33 which are coupled together over liquid seals 34. An inlet valve 35 is provided as shown so that oil may flow into the cylinder. The spreader 36 ensures that the oil is brought quickly into contact with the inner surface of 65 the cylinder. Vacuum is applied over the duct 37. 38 is a float valve which normally opens the duct 37 to the body of the cylinder 33. Should, however, there be an excess of oil in this cylinder the float would be raised to cut off communication between the cylinder and the duct 70 37 so that there is little danger of oil passing through the suction duct. The oil traversing the large surface of the fluted cylinder 33 loses a large proportion of its occluded gas. Reaching 75 the oil seal 34 the partially degasified oil may

pass forward to the next cylinder 39 which is similar to 33. As many such stages as desired may be used. The oil being finally withdrawn from the outlet valve 40.

A modified form of system is illustrated in Figure 3, wherein in this case twin cylinders are employed working in opposing phase. The operation of the pistons of these cylinders may be identical with that already described in connection with Figure 1 and will therefore not be further elucidated. In this figure oil from the reservoir 41 may pass through pipe 60 into either of the chambers 42 or 43 according to the motion of the pistons in these chambers. The device affording communication between the chambers 15 42 and 43 and the degasifiers and reservoirs is clearly illustrated and it is thought that the construction of the system will be readily understood from a description of its mode of operation. Assuming that the clutch has just engaged the motor 44 the piston 45 would begin to rise. In doing this oil would be sucked in through non-return valve 61 from the pipe 46 leading from the reservoir 47. This reservoir 47 receives degasified oil of the second 25 stage from the degasifier 48. On this upstroke of the piston 45 oil is forced from above said piston through valve 62 over pipes 49, 63 and 64 into the degasifier 48. During the time the piston 45 is ascending, the piston 50 in chamber 43 30 descends. In so doing a charge of oil is taken into the upper part of chamber 43 from the reservoir 41 through pipe 60 and non-return valve 65 and below the piston 50 oil is discharged through valve 66 into a duct 51 leading to a 35 cock 52 attached to the cable which is being impregnated. A supply of oil is also sent through pipe 67 surrounding duct 51 and into the ducts 53 and 68 for sealing valves 69 and 70 in a manner such as described in connection with Figure 1. A pipe 72 connecting pipe 67 to pipe 63 serves as a pressure relief in the valve sealing system, a hand operated valve 73 being provided in pipe 72 to regulate the flow of oil therethrough. In the reverse movements of the pistons 45 and 50 an action takes place similar to the above, the roles of the two pistons being reversed, and it will thus be seen how oil may be fed from a supply tank (not shown) through a pipe 74 containing a hand operated regulating valve 75 into the rough degasifier 54, be passed through the fine degasifier 48 and finally be pumped into the cock 52. Each of the pistons 45 and 50, in addition to being provided with weights 26, 26 as is the piston in Figure 1, is 55 surrounded by a compressible bellows-like stuffing box 76 which serves to prevent leakage of oil.

Although the invention has been described with reference to specific embodiments it is to 60 be understood that many modifications may be made without exceeding the scope of the invention.

What we claim is:

1. The process of impregnating a cable with 65 oil which comprises drawing the oil from a source of supply, degasifying the oil so drawn, feeding such degasified oil under pressure to the cable, and regulating the rate of degasification in accordance with the rate of consumption of 70 oil by the cable.

2. The impregnating process according to claim 1 characterized by the step of automatically maintaining the degasified oil at a substantially uniform pressure as it is fed to the cable 75

irrespective of the rate of oil consumption thereby.

3. Apparatus for feeding degasified oil into a cable comprising in combination a pump, an oil source, a degasifier, connecting means for a cable to be impregnated, and means for causing said pump to discharge degasified oil from the degasifier into the cable connecting means and to discharge oil from said source into said degasifier for degasification.

4. Apparatus for forcing degasified oil into a cable from degasifying units characterized in this that the feeding of the oil to the cable and to the degasifying units is effected by one and the same pump.

5. Apparatus as claimed in claim 3 characterized by the provision of means for causing the pump to operate under gravitational force.

6. Apparatus as claimed in claim 3 wherein a plurality of pumps are employed to render the feed to the cable continuous.

7. An arrangement for feeding degasified oil to a cable comprising a first stage degasifier, a second stage degasifier, a pump for controlling and effecting the flow of oil from the first degasifier to the second degasifier at a rate closely approaching that of absorption by the cable connecting means, and means for delivering the gasified oil from the second degasifier to the cable connecting means.

8. An arrangement according to claim 7 wherein a pressure compensating chamber works with said pump to maintain the requisite pressure of supply in different parts of the system.

9. A degasifier for use in an arrangement according to claim 7 characterized by having a plurality of fluted cylinders in stages, a liquid seal adapted to couple two adjacent cylinders, an inlet duct for the first cylinder, an outlet duct for the last cylinder, and means for applying vacuum to each stage whereby oil introduced through the inlet duct and traversing each stage in turn reaches the outlet duct in a degasified state.

10. Apparatus for feeding degasified oil into a cable comprising a plurality of fluted cylinders in

stages, a liquid seal adapted to couple two adjacent cylinders, means for applying vacuum to each stage, means adapted to introduce oil into each stage in turn, means adapted to prevent oil from having access to the vacuum ducts, cable connecting means, and means to deliver the degasified oil to the cable connecting means.

11. Apparatus for feeding degasified oil into a cable comprising a plurality of fluted cylinders in stages, a liquid seal adapted to connect two stages, means for applying vacuum to each stage, means adapted to introduce oil into each stage in turn, a float valve adapted to prevent oil from having access to the vacuum ducts, means adapted to bring oil into intimate contact with the walls of the fluted cylinders, and means for delivering oil from the last stage into the cable.

12. Apparatus for feeding degasified oil into a cable comprising an array of degasifier units adapted to permit ready assembly of units according to the desired capacity, each unit comprising a plurality of fluted cylinders in stages, a liquid seal adapted to couple the adjacent cylinders, inlet and outlet ducts, means for applying vacuum to each stage whereby oil traversing each stage in turn reaches an outlet duct in a degasified state, cable connecting means, and means for delivering degasified oil from the last degasifier station to the cable connecting means.

13. The process of impregnating a cable with oil which comprises obtaining the oil from a source of supply, degasifying the oil so obtained, feeding the degasified oil under pressure to the cable, and determining and regulating the rate of degasification by the rate of consumption of the oil by the cable.

14. The process of impregnating a cable with oil which comprises obtaining the oil from a source of supply, degasifying the oil so obtained, feeding the degasified oil under pressure to the cable, controlling the continuous degasifying of the oil during consumption of the degasified oil by the cable and regulating the rate of degasification in accordance with the rate of consumption.

THOMAS ROBERTSON SCOTT.
